(54) **GARMENTS, MARKING OUT & CUTTING**

(76) Inventor: **John Pudey**

John Padney Waterford New York

Letters Patent

The whole referred to in these Letters Patent and making part of the same containing a description in the words of the said John Padney himself of his Improvement, being an instrument for determining the points in making out & cutting garments called the American System.

It is known that John Padney of Waterford in the County of Donegal, &c. &c. of New York have made a new and useful improvement, being an instrument for determining the points in making out & cutting garments called the American System, which is described as follows.

My improvement consists principally in adding to the common square, a piece of wood or metal in the form of a segment of a circle, and mercantile tongue piece or delineator marked off or graduated in the manner hereafter described. The square may be twenty four inches long the four sides and a fourth of an inch thick. The third part of it may be six inches long & the same width and thickness. On both sides is marked a hole grubbed half inches and quarter inches. At figure 12 the center of the square is marked the letter A at 13 & B at 13.5 and so on to the end of the alphabet, denoting different sizes for different persons.

The segment of a circle or brace is the segment of a circle about twelve inches in diameter composed of two pieces each an inch wide placed one eighth of an inch apart, leaving a space between them for the tongue or delineator which is secured to the two sides of the square by screws, or by any other fastening.

The mercantile tongue piece or delineator is made of wood or metal like the rest of the instrument, of twenty three and a quarter inches long three quarters of an inch wide and one sixteenth of an inch thick. It is secured to the two corners of the square by a screw or pin, on which it turns and moves between the two pieces of a segment of a circle from one side of the square to the other describing a quarter circle; and when set in place fits into a groove on the

side of the square. At the end of the tongue is a small nail or projection to lay hold of in removing it from the groove. This tongue piece or steel in color has several rows or columns of letters, and figures marked on each side for determining the points in marking out a garment to be cut. Lines, diverging from the corners, of the square or center of the piece on which the moveable tongue piece stands, are marked upon the segment pieces with words or figures against each line signifying the use of it. These lines are to denote the position of the tongue piece in determining points, and are formed by cutting the garment by one rule, for the largest and smallest points or by marking them upon paper or cloth, letting certain lines of both touch the square, or corner of the garment. To the, placing the square upon the corner of the cloth or paper, & moving the tongue to the first point of the garment when the points of both garments, will be found to diverge from one another, if marked correctly.

He will then mark upon the segment, a line, diverging from a center to these points, and words or figures against it signifying its use. The tongue being divided into five or more equal parts, you will mark or set the tongue, at the largest and smallest points for garments, and then be letters or figures at each dot or mark for the different sizes between the largest, and small-est, in all twenty four more if necessary. You will proceed in this manner with all the required lines & points for marking garments once upon one side of the segment & tongue piece & the rest upon the other.

The inner edge or concave of the segment answers the purpose of marking the tip of the back to lay out, this being a dot or figures or letters to ascertain the width of the back.

There may be two or more small tongue pieces or dividers with corresponding segment pieces. It is another illustration of my invention & subject the drawing and model of the same deposited in the Patent office.

What I claim as my invention, and wish to secure by letters Patent is the above described instrument for determining the points in marking out and cutting garments called the American system. In testimony whereof I have hereunto subscribed my name before the witnesses and witnesses to the same
